UNITED STATES PATENT OFFICE.

ALEXANDER T. BROWN, OF SYRACUSE, NEW YORK.

TYPE-WRITING MACHINE.

965,501.

Specification of Letters Patent. Patented July 26, 1910.

Original application filed July 25, 1906, Serial No. 327,706. Divided and this application filed March 7, 1910. Serial No. 547,696.

To all whom it may concern:

Be it known that I, ALEXANDER T. BROWN, citizen of the United States, and resident of Syracuse, in the county of Onondaga and 5 State of New York, have invented certain new and useful Improvements in Type-Writing Machines, of which the following is a specification.

My invention relates to typewriting machines and the object of said invention may 10 be generally stated to be to simplify certain features of the construction such as the escapement and carriage release mechanism and the ribbon vibrator mechanism. 15 To the above and other ends which will hereinafter appear, my invention consists in the features of construction, arrangements of parts and combinations of devices to be hereinafter described and particularly pointed 20 ed out in the appended claims.

In the accompanying drawings wherein like reference characters indicate corresponding parts in the various views, Figure 1 is a vertical longitudinal sectional view 25 taken centrally through the machine and disclosing a sufficient number of parts of the machine to illustrate my invention in its embodiment therein. Fig. 2 is a fragmentary sectional view showing one of the guides 30 for the universal bar.

This case is a division of my application Serial No. 327,706, filed July 25, 1906.

The frame of the machine comprises a base 1, corner posts 2 and a top plate 3. 35 Key levers 4 are pivoted at 5 to depending hangers 6 secured to a member 7 supported on the base of the machine. The key levers are each provided with a finger piece 8 and extend rearwardly of their pivots and terminate at their rear ends in a single line transversely of the machine. Each key lever has a depending arm 9 hooked at its lower end as indicated at 10 where it is connected to one end of a contractile spring 11, the spring 40 being connected at its opposite end to a rod 12 secured to the base of the machine. The rear end of each key lever is pivoted at 13 to a link 14 which in turn is pivoted at its rear end as at 15 to an upright sub-lever 16. The sub-levers 16 are pivoted at 17 to 45 hangers 18 secured to the frame of the machine. Pull links 19 extend forwardly from the upper ends of the sub-levers and are pivotally connected at 20 with the segmentally arranged upwardly and rearwardly

striking type bars 21. Each type bar 21 is provided with a rearwardly extending arm 22 adapted to be received in a bifurcated type guide 23 formed on the associated type bar hanger 24. The various 50 type bar hangers are secured to a segment 25 which in the present instance is adapted to receive a shifting movement to change the case position of the type bars. The type bars are supported at their forward ends by 55 a pad 26 mounted on a segmental support 27 connected to receive a vertical movement with the type bar segment. A universal bar 28 is arranged above and transversely of the key levers 4 at the rear ends thereof. This 60 universal bar is connected to depending links 29 which are guided in loops formed at the inner ends of bracket arms 29^a (Fig. 2) secured to the side plates of the base. The lower ends of the links 29 are pivoted 65 to rearwardly extending crank arms 30 which project from a rock shaft 31 mounted to turn on bearing screws 31^a threaded through tapped openings in the base of the machine.

Each key lever 4 and its associated link 13 constitute a toggle, the members of which are in line in the normal position thereof as shown in full lines, the toggle being broken and moved to the dotted line position on the depression of a key, to effect an actuation of the associated sub-lever 16 and thus move the connected type bar to the printing position.

The rock shaft 31 is also provided with a 70 rearwardly extending centrally disposed crank arm 32 connected at its rear end with an upwardly extending pull link 33 which in turn is pivotally connected at 34 with a lever 35 pivoted at 35^a to a depending 75 bracket 36 on the top plate of the machine, the lever extending fore and aft of the machine and being horizontally disposed and situated directly beneath the top plate. This lever 35 is a lever of the first order and is 80 pivotally connected at its forward end with a ribbon vibrator 37 guided in its vertical movement by a bracket 38 secured to the top plate 3 of the machine at 39. The rear 85 end of the lever 35 carries feed dogs 40 which are preferably formed integral with the lever, the uppermost of said dogs being bent laterally to bring them out of alignment. The lever 35 is also formed with a 90 depending arm 41 to which the forward end 95 of

110

of a contractile spring 42 is connected, the rear end of said spring being connected to a threaded rod 43 which passes freely through an opening in a bracket 44 secured 5 to the top plate of the machine at 45. A thumb nut 46 is received on the rear end of the threaded rod 43 to effect an adjustment of the rod and a corresponding adjustment of the spring 42 to vary the force of the 10 spring on the lever 35. The feed dogs 40 coöperate with an escapement wheel 47 disposed in a horizontal plane directly beneath the top plate. The escapement wheel is connected with a vertically disposed shaft 48 15 by a set screw 49 which is received in a threaded opening in a hub 50 of the escapement wheel and bears at its inner end against the shaft 48. The shaft 48 passes through the top plate, being received in a 20 hollow post 51 which projects upwardly from the top plate of the machine in the rear of the carriage. A collar 52 is secured to the shaft 48 by a pin 53 to support the shaft in place. The collar 52 and the hub 50 of 25 the escapement wheel coöperate with the bearing for the shaft 48 to prevent a longitudinal movement of the shaft in its bearing. A feed pinion 54 is received on a shaft 48 and loosely surrounds the same, the pinion being provided with a depending supporting hub or portion 55 which bears at 30 its lower end against the sleeve 52. The pinion is also provided with upwardly extending ratchet-like teeth 56 which form one section of a two-part clutch. The other section of this clutch is formed by teeth 57 35 on a sleeve 58, which sleeve has a rectangular opening therein for coöperation with the rectangular portion 59 formed at the upper 40 end of the shaft 48. The upper end of the shaft is enlarged as indicated at 60 to prevent a displacement of the clutch section 58 from the shaft 48. Sufficient upward movement, however, is afforded the clutch section 58 along the squared portion of the 45 shaft 48 to disengage the teeth 57 from the teeth 54 on the feed pinion. The clutch member 58 is likewise provided with a circumferential flange 61 beneath which is received a flange 62 formed on a bar 63 which 50 extends throughout the length of the carriage and is preferably formed as a cross bar or bail provided at its ends with arms 64 pivoted at 65 to end plates 66 of the carriage.

One or both of the arms 64 may be extended forwardly beyond their pivots to form release levers 67 provided at their forward ends with finger pieces 68. Each arm 60 67 is preferably slotted at 69 to receive a pin 70 which projects outwardly from a side plate 66 of the carriage. A depression of either finger piece or release key 68 is effective to move the clutch section 58 upwardly out of engagement with its com-

panion clutch section to release the feed pinion 54. The carriage is then free to be moved in either direction independently of the escapement mechanism, the pinion 54 being revolved at this time freely on the shaft 48 through the constantly maintained geared connection between the pinion and a feed rack 78 on the carriage. When, however, pressure is released on the depressed key 68 a suitable spring is effective to restore the parts to normal position, lowering the clutch section 58 in engagement with its companion clutch section on the feed pinion. This engagement of the clutch sections positively connects the feed pinion to rotate 80 with the shaft 48 through the engagement of the clutch section 58 with the squared portion of the shaft. The carriage which is driven by a spring drum (not shown) may be of any suitable construction but the carriage shown in the present instance is somewhat similar to that disclosed and claimed in my Patents Nos. 910,987 and 935,776, dated respectively Jan. 26, 1909 and Oct. 5, 1909. The carriage comprises two angular 90 plates 71 and 72 grooved for the reception of anti-friction balls or rollers 73 which are likewise received in opposite grooved faces 74 of a track or guide bar 75 secured to upright projections 76 which extend from the 95 top plate of the machine. A paper table 77 is secured to the members 71 and 72 of the carriage and the feed rack 78 is fixedly connected to the carriage and is at all times maintained in mesh with the feed pinion 54. 100 A cylindrical platen 79 is mounted in a carriage in the usual or any suitable manner.

At one or both sides of the machine I have provided key levers 80 each provided with a depending arm 81 hooked at its 105 lower end as at 82 to pass beneath and engage the associated crank arm 30. The forward ends of these levers 80 are connected to the usual space key 83. The levers 80 like the key levers are pivoted intermediate their 110 ends to hangers such as the hangers 6 so that a depression of the space bar is effective to elevate the rear ends of the levers 80 and cause a corresponding elevation of the crank arms 30, thus effecting an actuation of the 115 rod 33 which is effective to vibrate the lever 35, to elevate the ribbon vibrator and to move the rear end of the lever 37 as indicated in dotted lines to actuate the escapement mechanism.

It will be seen from the foregoing description that the single lever 35 which may be made of sheet metal constitutes a combined dog ricker, feed dogs and ribbon vibrator actuating lever and that the movement of this lever around its pivot is effective to actuate the feed dogs and the ribbon vibrator. Moreover, it will be seen that the escapement mechanism and the means for releasing it through the bail 63 constitute a 130

simple and efficient construction comprising but few parts.

Various changes may be made without departing from the spirit and scope of my invention.

What I claim as new and desire to secure by Letters Patent, is:—

1. In a typewriting machine, the combination of a lever, a ribbon vibrator carried directly by said lever, and feed dogs also carried directly by said lever.

2. In a typewriting machine, the combination of a key actuated lever of the first order, a ribbon vibrator carried by said lever at one end thereof, feed dogs carried by said lever at the other end thereof, and a rack co-operating with said feed dogs.

3. In a typewriting machine, the combination of a key actuated lever, a ribbon vibrator carried by said lever, feed dogs formed integral with said lever, and a rack co-operating with said feed dogs.

4. In a typewriting machine, the combination with the top plate of the machine, of a key actuated lever mounted directly beneath the top plate, a ribbon vibrator carried by said lever, feed dogs carried by said lever, and a rack co-operating with said feed dogs.

5. In a typewriting machine, the combination with the top plate of the machine, of a key actuated lever pivoted directly beneath said top plate, a ribbon vibrator connected directly to said lever at one end thereof, feed dogs formed integral with said lever at the other end thereof, and an escapement wheel with which said feed dogs co-operate.

6. In a typewriting machine, the combination of an escapement wheel situated beneath the top plate of the machine, a vertically disposed shaft to which said escapement wheel is secured and which extends through

said top plate and is supported in a bearing on said top plate, a feed pinion near the upper end of said shaft, said pinion having a clutch member thereon, a second clutch member fixed to turn with said shaft but free to move longitudinally thereof to effect an engagement and disengagement between said clutch members, hand actuated means carried by the carriage and co-operating directly with said movable clutch to release the carriage, and a substantially horizontally disposed lever situated beneath the top plate and carrying at one end thereof feed dogs which co-operate with said escapement wheel.

7. In a typewriting machine, the combination of an escapement wheel situated beneath the top plate of the machine, a vertically disposed shaft to which said escapement wheel is secured and which extends through said top plate and is supported in a bearing thereon, a feed pinion near the upper end of said shaft, said pinion having a clutch member thereon, a second clutch member fixed to turn with said shaft but free to move longitudinally thereof to effect an engagement and disengagement between said clutch members, a bail pivoted to the carriage and co-operating with said movable clutch and adapted to release the carriage, and one or more finger pieces connected directly to or formed integral with said bail for actuating it.

Signed at Syracuse, in the county of Onondaga and State of New York, this 4th day of March, A. D. 1910.
